UNITED STATES PATENT OFFICE.

WILLIAM P. HAMMOND, OF NEW YORK, N. Y.

COMBINED VALVE-CAP AND DUST-GUARD FOR PNEUMATIC-TIRE VALVES.

1,114,257.

Specification of Letters Patent. Patented Oct. 20, 1914.

Application filed March 17, 1913. Serial No. 754,946.

To all whom it may concern:

Be it known that I, WILLIAM P. HAMMOND, citizen of the United States, residing at New York, in the county of New York and State of New York, have invented certain new and useful Improvements in Combined Valve-Caps and Dust-Guards for Pneumatic-Tire Valves, of which the following is a specification.

The present invention relates to a combined valve cap and dust cap for the valve casings of pneumatic tires, and has for its object to provide a device of this character which embodies novel features of construction whereby the two caps are combined in one structure so as to be simultaneously placed in position or removed therefrom, thereby eliminating the annoyance and vexatious loss of time usually incident to handling the two caps separately and independently of each other.

A further object of the invention is to provide a combined valve cap and dust cap which is comparatively simple and inexpensive in its construction, which can be quickly placed in position or removed therefrom, and which provides an effective means for closing the end of the valve casing and also for housing the projecting portion of the valve casing so as to exclude dust and dirt therefrom.

With these and other objects in view, the invention consists in certain novel combinations and arrangements of the parts as will more fully appear as the description proceeds, the novel features thereof being pointed out in the appended claims.

For a full understanding of the invention, reference is to be had to the following description and accompanying drawing, in which:

Figure 1 is a side elevation of one embodiment of my combined valve cap and dust cap, portions being broken away and shown in section to more clearly illustrate the construction. Fig. 2 is a side elevation of a modified form of the invention, parts being broken away and shown in section to more clearly illustrate the details of construction.

Corresponding and like parts are referred to in the following description, and indicated in all the views of the drawings by the same reference characters.

One embodiment of my invention is illustrated by Fig. 1, in which the numeral 7 designates the dust cap. This dust cap has

a threaded engagement with the reduced extremity 1^b of the valve casing 1 and is adapted to be applied to or removed therefrom in the usual manner. The mouth of the valve cap 7 is flared and enlarged as indicated at 8 to provide a substantially cylindrical recess which surrounds the tubular valve casing 1 and is adapted to receive the upper end of the sleeve or dust excluding casing 9. This sleeve 9 loosely receives the valve casing 1 and the exterior thereof is provided with left hand threads 9^a which engage corresponding threads formed upon the interior of the flared end 8 of the valve cap 7. The free or lower end of the sleeve 9 is adapted to be brought into engagement with the rim nut 3, while an intermediate portion of the sleeve is formed with an annular and milled enlargement 10 which can be readily grasped by the fingers when adjusting or manipulating the sleeve. The valve cap 7 and dust excluding casing 9 are thus combined in one member which is handled as a unit, both the cap and dust guard being removed from the valve casing or applied thereto at the same time. The valve cap 7 is first applied to the reduced end 1^b of the valve casing 1 and the sleeve 9 then rotated in a reverse direction until the mouth thereof is brought into a firm engagement with the rim nut 3. Owing to the provision of the left hand thread 9^a, any loosening of the rim nut 3 is prevented, since the unscrewing of the rim nut would tend to rotate the sleeve 9 in such a direction as to bring the sleeve into a more forcible engagement with the rim nut, it being remembered that the cap 7 is connected to the valve casing 1 by means of right hand threads, while the sleeve 9 is connected to the cap 7 by means of left hand threads.

A modification is shown by Fig. 2, in which the rim nut 3 is provided with an interiorly threaded recess 3^b surrounding the tire valve casing 1. The valve cap 13 is threaded upon the reduced extremity 1^b of the tire valve casing 1 in the usual manner, the mouth of the valve cap being enlarged and flared as indicated at 13^a. The dust excluding sleeve 14 is adapted to loosely receive the tire valve casing 1, the upper end having a telescoping engagement with the flared mouth 13^a of the valve cap 13. The upper extremity of the sleeve 14 is provided with an exterior rim 14^a which cooperates

with an inwardly extending flange 13^b upon the flared end 13^a of the valve cap 13 for preventing the telescoping members from pulling completely apart. The lower end of 5 the dust excluding sleeve 14 is threaded at 15 and is adapted to be received within the recess 3^b of the rim nut 3 and to have a threaded engagement with the walls thereof. The valve cap 13 is first applied to the 10 extremity of the valve casing 1, and the telescoping dust excluding sleeve 14 is then moved downwardly against the rim nut 3 and rotated to bring the threaded end 15 thereof into engagement with the threaded 15 walls of the recess 3^b.

Having thus described the invention, what I claim as new and desire to secure by Letters Patent, is:—

1. In a combined valve cap and dust 20 guard for tire valve casings, the combination of a threaded cap adapted to be screwed upon the outer end of the tire valve casing, and a dust excluding sleeve carried by the cap so as to be removable therewith, the end 25 of the dust excluding sleeve being adjustable upon the cap to admit of the said sleeve being brought into engagement with the rim nut after the cap has been screwed into position.
2. In a combined valve cap and dust 20 guard for tire valve casings, the combination of a threaded cap adapted to be screwed upon the tire valve casing, said cap being formed with a flared mouth, and a dust ex-

cluding sleeve carried by the cap so as to be 35 removable therewith, the end of the sleeve engaging the flared mouth of the cap and being movable in and out therein to admit of the sleeve being brought into engagement with the rim nut after the cap has 40 been screwed into position.

3. The combination of a cap for tire valve casings, and a dust excluding sleeve carried by and having a threaded engagement with the said cap, the dust excluding sleeve 45 being adapted to engage the rim nut.

4. The combination of a cap for tire valve casings, said cap being formed with a flared mouth, and a dust excluding sleeve having one end thereof threaded within the flared 50 mouth of the valve cap while the opposite end thereof is adapted to engage the rim nut.

5. The combination of a cap for tire valve casings, said cap having a flared mouth and being provided with left hand threads, and 55 a dust excluding sleeve carried by the valve cap and provided with left hand threads adapted to engage the left hand threads of the valve cap, the said dust excluding sleeve being adapted to be brought into engagement with the rim nut.

In testimony whereof I affix my signature in presence of two witnesses.

WILLIAM P. HAMMOND.
